UNITED STATES PATENT OFFICE.

LESLIE N. CRICHTON, OF SALT LAKE CITY, UTAH, ASSIGNOR TO WESTINGHOUSE ELECTRIC AND MANUFACTURING COMPANY, A CORPORATION OF PENNSYLVANIA.

FUSE FOR HIGH-TENSION ELECTRICAL CIRCUITS.

1,300,249.

Specification of Letters Patent. Patented Apr. 15, 1919.

Application filed January 25, 1913. Serial No. 744,179.

To all whom it may concern:

Be it known that I, LESLIE N. CRICHTON, a citizen of the United States, residing at Salt Lake City, in the county of Salt Lake 5 and State of Utah, have invented a new and useful Fuse for High-Tension Electrical Circuits.

My invention relates to electrical fuses and especially to those used on high tension 10 electrical circuits. It has for its object the production of a fuse for the purpose stated, which shall be efficient and economical, which may be safely used out doors if desired, and which will be useful in any other 15 location where moisture is present in the atmosphere to such an extent as to render useless ordinary expulsion fuses.

It has been found by experience that entirely open fuses will not operate satisfactorily on relatively high voltages, hence for 20 relatively high voltage circuits it has become general practice to inclose the fuse wire in an insulating tube which is strong enough to stand the high pressure due to the vaporizing of the fuse metal. Glass and porcelain have been found to be unsatisfactory for 25 such service, so tubes made of fibrous materials are usually used. Such tubes are unsatisfactory for outdoor use because they become slightly conducting when they are wet 30 so that in case the fuse inside the tube should blow, the current will still leak into the circuit beyond the fuse. This usually causes an arc to form on the outside of the tube. 35 It has therefore been customary to rigidly fasten each end of the fuse wire with the tube slipped over the wire and supported by it in such a way that when the fuse blew the tube would fall to the ground. However, 40 such a scheme precludes the use of small fuses, because of their mechanical weakness and even large fuses are frequently broken out by heavy winds.

In order to overcome these disadvantages 45 and in so doing to attain my objects above stated, I inclose my fuse wire for a part of its length between terminals within a protecting tube or tubes, supported upon one or more insulators independently of the fuse 50 wire. When the fuse blows, the length of fuse wire which is outside of the inclosure is destroyed and the inclosure itself may be partly destroyed, but in either case a gap is formed which cannot be bridged by moisture

and across which a permanent arc cannot be 55 maintained.

Figures 1 and 2 show in elevation two forms of my invention.

Referring to Fig. 1; 1 is a piece of flexible tubing fastened to a couple of metal insulator caps 2, 3 by means of the screws 4, 4, 4, 4. The metal caps may be fastened to the insulators 11 and 12 by cement, tie wires, or other methods. The flexible tube 1 prefer to be of the kind which is commonly used by 65 electricians and which consists largely of cotton fabric woven on a circular loom.

One of the line wires 5 is fastened to the insulator cap 3. The other line wire 6 is fastened to an insulator 7. The fuse wire 8 70 is threaded through the tube and each end fastened to the line wires 5 and 6. This fuse is preferably composed of some non-corrosive wire such as tinned copper.

The action of the fuse is as follows: 75

When the fuse melts an arc is formed inside the tube which is explosively blown out in a very short interval of time. The short length of fuse which is outside the tube and between the insulator cap 2 and the line wire 80 6 is also destroyed. The result is that there is left a gap in the circuit so that no leakage can occur no matter how wet the tube may be. The length of the gap between 2 and 6 85 should of course be greater than the spark- ing distance of the circuit voltage.

Fig. 2 shows another form of my invention which might be more economical because it eliminates one of the insulators shown in Fig. 1. It is also more likely to be applicable to extremely high voltages because it has two tubes in series. The arrangement shown in Fig. 2 differs from that in Fig. 1 in that two rigid insulating tubes 9 and 10 are substituted for the flexible tube 1. In 90 this case the blowing of the fuse causes a gap to occur between the tubes 9 and 10. One advantage of such an arrangement is that in case the section of fuse wire which is across the gap does not melt when the sections inside the tubes blow, it will, of its own weight, fall clear of the tubes.

My invention can of course be applied to other types of insulators and can be varied in numerous other ways. Besides being useful for outdoor operation, my invention is useful in any location where an ordinary expulsion fuse is liable to be rendered use-

less by a deposit of moisture or other conducting material.

I claim as my invention:

1. A fuse comprising a pair of terminals, a pair of insulators supporting the same, a pair of expulsion tubes supported on the insulators but separated by an air gap and open to the air at both ends, and a fusible conductor secured to the terminals and passing through the expulsion tubes.
2. A fuse comprising two insulated terminals, two expulsion tubes open at both ends to the air and secured to the respective terminals, and a fusible conductor secured to the terminals and extending through the expulsion tubes.
3. A fuse comprising two terminal members, two expulsion tubes open at both ends to the air, and a fusible conductor extending through the said tubes.
4. A fuse comprising terminals having a gap between them, a fusible element bridging the terminals, and expulsion tubular means open to the air at both ends supported independently of the fusible element and inclosing the same for a portion of its length.
5. The combination with two insulators having fuse terminals thereon, of a fusible conductor connected between the terminals and a plurality of tubular members that are open at both ends to the air supported by the insulators and adapted to surround the fusible conductor, said tubular members being of such length that a gap is left between them to preclude reestablishment of an arc due to leakage thereacross when the conductor is fused.
6. A fuse comprising terminals having a gap therebetween, a fusible element bridging the terminals with a dip downward, and a pair of expulsion tubes, each supported rigidly on an insulator, with their adjacent ends inclined downwardly toward each other but separated by a gap, said tubes inclosing opposite portions of the fusible element, but leaving the same exposed in the gap.
7. A fuse comprising a pair of terminals, a pair of insulators supporting the same, a pair of expulsion tubes supported on said insulators by their outer ends and dipping downward with their inner ends approaching but not meeting on the sides of a figure V, and a fusible conductor secured to said terminals and passing down through one tube across the gap between them and up through the other.
8. The combination with two insulators having fuse terminals thereon, of a fusible conductor connected between the terminals and adapted to sag at a point intermediate its ends, and a plurality of tubular members open to the air at both ends and supported by the said insulators, said tubular members being adapted to surround the fusible con-

ductors and to be disposed a predetermined distance apart.

9. The combination with a plurality of insulators, and a fusible conductor operatively connected thereto, of a plurality of tubular members mounted on the said insulators and adapted to surround the fusible conductor, said tubular members being open to the air at both ends and separated a predetermined distance apart. 70

10. The combination with two insulators and a fusible conductor operatively connected thereto and adapted to sag therebetween, of tubular members that are open to the air at both ends adapted to loosely surround the fusible conductor and to be supported by the insulators, said tubular members being disposed a predetermined distance apart. 75 80

11. The combination with a pair of conductor terminals, of a fuse comprising a pair of insulating members independently supported, one upon each of said conductor terminals, one of said insulating members having an opening formed therethrough directed toward the other insulating member, a fuse wire extending between said insulating members and extending through said opening having its opposite ends connected to said conductor terminals. 85 90

12. A fuse comprising a pair of insulating members spaced apart, a pair of supporting members one for each of said insulating members, means whereby one of said insulating members is adjustable toward and away from the other of said insulating members in the plane of a straight line extending between said supporting members, a fuse wire extending between said insulating members, and means for connecting conductor terminals to opposite ends of said fuse wire. 100 105

13. A fuse comprising a pair of insulating members spaced apart, means whereby one of said insulating members is adjustable relatively to the other of said insulating members, a fuse wire extending between said insulating members, one of said insulating members having an opening therethrough through which an intermediate portion of said fuse wire extends, and means for connecting conductor terminals to opposite ends of said fuse wire. 110 115

14. A fuse comprising a pair of conductor members spaced apart and intended to be protected, an elongated insulating member having a tube-like aperture longitudinally therethrough, said insulating member being interposed in the path of a line extending between said members to be protected so that the aperture thereof extends transverse to such line, and a fuse wire extending from one of the members to be protected to one end of the insulating member and continuing through the aperture of the insulating member and from the opposite end of the 120 125 130

insulating member to the second member to be protected.

15. A fuse comprising a pair of conductor members spaced apart and intended to be protected, and a pair of elongated insulating members each having a tube-like aperture longitudinally therethrough, said insulating members being interposed in the path of a line extending between said members to be protected so that the apertures of said members extend transverse to such line, and a fuse wire extending from one of the members to be protected to one end of one of said insulating members thence through the aperture of said insulating member to the opposite end thereof thence to one end of the second insulating member and through said second insulating member continuing out of the second end of said second insulating member to the second member to be protected.

16. A fuse comprising a pair of conductor members spaced apart and intended to be protected, and a pair of elongated insulating members each having a tube-like aperture longitudinally therethrough, said insulating

members being interposed in the path of a line extending between said members to be protected so that the apertures of said members extend transverse to such line, a fuse wire extending from one of the members to be protected to one end of one of said insulating members thence through the aperture of said insulating member to the opposite end thereof thence to one end of the second insulating member and through said second insulating member continuing out of the second end of said second insulating member to the second member to be protected, and said insulating members being arranged in inclined relation to each other so that the apertures thereof at the ends of the insulating members adjacent the members to be protected are farther spaced apart than the remaining ends of the insulating members, for the purpose described.

In testimony whereof, I have subscribed my name this 20th day of January, 1913.

LESLIE N. CRICHTON.
